WASHING MACHINE

James B. Kirby, West Richfield, Ohio, assignor to The Apex Electrical Manufacturing Co., as trustee, Cleveland, Ohio, a corporation of Ohio

Continuation of application Serial No. 619,849, October 2, 1945. This application April 5, 1954, Serial No. 421,097

29 Claims. (Cl. 8—159)

My invention relates to laundering and concerns particularly washing of fabrics and the like.

Among the objects of my invention are to wash flexible fabric articles such as clothes expeditiously, thoroughly, and without damage; to dry such articles expeditiously, speedily, with a high degree of extraction, and without damage, and to carry on both such washing and drying operations in the same receptacle.

A further object of my invention is to carry out washing or cleansing operations with a high degree of economy of cleansing liquid such as dry-cleaning fluid or washing water, fuel for heating water, soap or other detergent, and mechanical driving power. It is also an object of my invention to provide a mechanical washing and drying arrangement in which no more power is required for drying than for washing.

A further object of the invention is to provide improved arrangements for washing, drying and rinsing articles without rehandling them between the washing and rinsing operations, or between the rinsing and drying operations.

A further object is to provide improved laundering methods and apparatus for efficiently washing and drying articles very quickly. Still another object is to provide such apparatus for automatic operation.

A further object is to increase the speed of the combination of steps in the method of washing, rinsing and extracting to shorten the cycle of operations.

Still another object is to shift from washing, to extracting and to rinsing speedily without shifting gears or delayed action so as to shorten the cycle.

A further object is to provide improved arrangements for carrying on washing or cleansing operations in which the manipulation of the articles to be cleansed is visible through steps of the operation.

A further object is to provide centrifugal handling arrangements with improved means for controlling vibration and for bringing the articles centrifuged up to speed without excessive vibration.

A further object is to provide washing arrangements with improved means for automatically maintaining an optimum supply of washing liquid.

A further object is to provide arrangements for supporting reciprocatory or rotary apparatus free from tendency for crawling or jumping without any need for fastening down to the floor.

Still another object of the invention is to provide alternatively for transmission of rotary motion to a driven object, such as a container, or conversion of rotary motion into reciprocatory motion. In addition it is an object to effect such conversion by opposing rotary motion of the driven object.

Other and further objects, features and advantages of the invention will become apparent as the description proceeds.

In carrying out my invention in accordance with a preferred form thereof, I subject damped clothes or other fabric articles to forces tending simultaneously to

2

oscillate them and redistribute them while driving air, washing fluid, or both through them. There is a substantially vertical oscillatory component of force for washing action, a circumferential component of force for distribution action on the clothes and a roll-over or inwardly overturning component of force for redistribution action. For drying, the clothes are revolved at sufficient speed to expel the major portion of the washing fluid.

For accomplishing these actions, the clothes or other articles are held in a container having liquid discharging openings in it and the same container is employed for holding the clothes during both the washing and drying operations.

In the preferred embodiment a single rotary driving member is employed for actuating the container to produce both the washing and drying actions, and means are provided for recirculating water through the container during the washing action. Mechanism is interposed between the driving member and the container for alternatively, either converting the rotary motion of the driving member into oscillatory motion of the container for washing action or rotating the container for drying action. The preferred mechanism is such that when the container is prevented from rotating, the oscillatory motion is produced and when the container is left free it rotates with the driving member. The mechanism is such as to impart to the container during washing action a rocking or seesaw motion rotatively progressing around its center, what may be described as vertical reciprocation of the container with successive portions of the container around its center being reciprocated in progressively different phase.

This application is a continuation of my co-pending application entitled "Washing Machine," Serial No. 619,849, filed October 2, 1945, which is a continuation-in-part of my application, Serial No. 526,154, filed March 13, 1944 and now Patent No. 2,520,366, issued August 29, 1950. Said application Serial No. 619,849 was allowed on September 13, 1954, and was permitted to become abandoned on March 13, 1955, in view of the presentation of the allowed claims of said Serial No. 619,849 in the instant application.

A better understanding of the invention will be afforded by the following detailed description considered in conjunction with the accompanying drawings, and the scope of the invention will be set forth in the claims.

In the drawings:

Fig. 1 is a vertical medial section through a washing and drying machine forming an embodiment of my invention;

Fig. 2 is an enlarged vertical section of the pedestal arrangement of the apparatus of Fig. 1;

Fig. 3 is a perspective view of one of the ribs which may be mounted in the container in the apparatus of Fig. 1;

Fig. 3A is a view of a cross-section represented as cut by a plane 3A—3A indicated in Fig. 3.

Fig. 4 is a fragmentary sectional view of a portion of the apparatus of Fig. 1, represented as cut by a plane 4—4, and showing yieldable control-shaft driving means;

Fig. 5 is a plane view of the apparatus of Fig. 1, with a portion of the top broken away to expose the interior mechanism shown partly in section;

Fig. 6 is a diagram illustrating the sequence of operation;

Fig. 7 is a plan view, partially in section, of the portion of the apparatus of Fig. 1 below the broken plane 7—7;

Fig. 8 is a vertical sectional view of a hydraulic stabilizer for one of the supporting feet in the apparatus of Fig. 1.

Fig. 9 is a cross-sectional view of the water feed and drainage arrangement of the apparatus represented as taken along a broken plane 9-9 indicated in Fig. 7;

Fig. 10 is an elevation of a pendular vibration-responsive switch for the apparatus;

Fig. 11 is a fragmentary plan view partially in section of a portion of the apparatus of Fig. 1 below the plane 11-11, illustrating the mechanism for holding and for retarding speed of rotation of the control shaft;

Fig. 12 is an elevation of the water-pressure responsive water-flow controlling mechanism of the apparatus;

Fig. 13 is a vertical sectional view of the portion of the speed-retarding mechanism represented as cut by plane 13-13 indicated in Fig. 11 and as seen by looking in the direction of the arrows, and:

Fig. 14 is a circuit diagram schematically representing a sequence-controlling time switch and parts of the mechanism controlled by the time switch.

Fig. 15 is a vertical sectional view corresponding to Fig. 1 but showing a side elevation of the fabric container instead of a section and illustrating an embodiment in which the washing-mechanism and tub for the water are slidably supported within an outer casing:

Fig. 16 is a fragmentary view of a modification in the arrangement of Fig. 15 in which the tub and carriage therefor are slidably supported some distance above the bottom of the enclosing casing:

Fig. 17 is a schematic diagram representing the portion of the apparatus of Fig. 16 below the section line 17-17; and

Fig. 18 is a fragmentary view of a modified movement providing limited sidewise freedom of motion.

Like reference characters are utilized throughout the drawing to designate like parts.

An illustrative embodiment of the invention as shown in the drawings and which will be described comprises a casing 21 within which are mounted a pedestal 22 for supporting a clothes container 23, a driving motor 24, container-driving and controlling mechanism 25, and other pieces of mechanism which will be pointed out particularly in connection with a detailed description of the apparatus. Brake and clutch mechanism for controlling the transmission of power from the motor 24 to the container 23 and for alternatively effecting the washing and drying action is represented generally by reference numeral 25 in Fig. 1. For automatically controlling and timing the sequence of operations, a time switch 26 is provided having manual starting knob 27.

For forming a water reservoir or tub 30 below the container 23, sheet metal pieces are provided including a cylindrical shell 20, a bottom 28 with a recessed portion 29 around the motor 24 having a raised wall 31 above the motor 24 jointed to the shell 20, and to a tubular sheet 32 surrounding the pedestal 22. The container 23 for clothes or other articles to be washed has a top opening 33 to permit articles to be washed to be placed therein or removed, and the casing 21 has a removable cover 34 which is preferably transparent.

As shown more clearly in Fig. 5 a water supply nozzle 35 is provided for directing water into the top opening 33 of the container 23 and a pair of nozzles 36 is provided for re-circulating water into the container 23. The casing 21 is provided with a base 37 comprising a relatively heavy metal plate serving to assist in minimizing vibration difficulties and also serving to support various other parts of the apparatus.

For supporting the casing 21 and the base plate 37 upon a horizontal surface 38 such as a floor in a home, for example, which may be composed of wood flooring, cement, or other surfaces subject to unevenness, feet 39 are provided preferably four in number, and one of the feet is provided with a self-leveling mechanism 41, preferably comprising a hydraulic stabilizer.

The container 23 is provided with openings to permit

continuous circulation of water through the mass of clothes or articles to be washed held in the container, and obstacles such as cleats or ribs 42 are provided which are fastened around the edges of the container 23 to retard circumferential motion of clothes around the container during the washing operation. Although the container 23 need not, necessarily, be circular as illustrated, it is preferably symmetrical with respect to a geometric axis 43, which is inclined to the axis of the pedestal 22, shown vertical. Preferably also the container 23 has a reentrant lower wall 44 in order to permit support of the container 23 and the control of the action thereof, at a point substantially coincident with the center of mass of the container. The container 23 is preferably composed of a suitable material which combines lightness with strength, such as sheet metal, for example, pressed aluminum. As illustrated, the reentrant lower wall portion 44 of the container 23 is composed of overlapping sheets of material such as pressed aluminum for the sake of added strength. If desired, the lower part of the container 23 may be composed of cast aluminum or magnesium alloy with the upper part drawn from sheet metal.

As shown more clearly in Fig. 2, a supporting hub 45 composed of suitable material such as steel plate, e. g. secured to the center of the reentrant lower wall portion 44, for removably mounting the container 23 at the upper end of the pedestal 22. The specific mounting arrangement illustrated will be described more in detail in connection with the description of Fig. 2. Preferably, a guard or cap 46 is mounted over the center of the container 23 for preventing clothes from being caught or having their movement in the container interfered with.

The water-draining openings in the container 23, particularly near the lower portion thereof are such in number and size as to retain a predetermined quantity of water within the container 23 during washing operation. The specific number and size of the openings depends upon the capacity of the apparatus for recirculating water through the nozzles 36. As will be explained more fully hereinafter, means are provided for automatically adjusting the rate of flow through the nozzles 36 in relation to the quantity of water drained from the container 23. Although the invention is obviously not limited to a specific arrangement, I found that satisfactory results may be obtained, in the case of a container about 22 inches in diameter with a 600 R. P. M. drive, where the container has 10 ribs, 42 evenly spaced around its periphery and secured to the walls of the container, with a row 47 of openings in the bottom wall of the container near the peripheral edge 48 thereof, an opening 47 being between each pair of ribs 42, and with rows of side openings 49, 51, 52 and 53 around the outer walls of the container 23. In the specific illustrative arrangement assumed, the row of openings 49 also consists of one opening between each pair of ribs 42, about one and one-half inches from the bottom edge 48, the row of openings 51 also consists of one opening between each pair of ribs 42 about three inches from the edge 48. The row of openings 52 about four and one-half inches from the edge 48 consists of two openings between each pair of ribs 42, and above the row 52 there may be one or more rows of openings 53 consisting of a considerable number of openings. The container 23 has an upper retaining portion 54 which preferably contains numerous openings considerably more numerous and larger than those in the lower portion of the container in order to facilitate expulsion of water during centrifugal drying operations.

As illustrated in Fig. 2, the pedestal 22 comprises a tubular portion 55, and a flange portion 56. For supporting the pedestal 22 a plurality of legs 57, preferably four in number in case of a square casing as illustrated, are bolted at the upper end to the flange 56 and at the lower end to the four corners of the base plate 37 of the

casing 21. The legs 57 are composed of a moderately rigid material such as cold-rolled steel strips, pressed to form, which provides the pedestal 22 with a high degree of stiffness with respect to bending action away from a vertical axis, but supply a slight degree of resiliency with respect to up and down or vertical motion along a vertical axis.

Rotatably mounted within the tubular portion 55 of the pedestal 22 are a tubular or hollow, rotating, drive shaft 58 and a control shaft 59, the latter being within the hollow shaft 58. For rotatably supporting the hollow shaft 58 within the pedestal 22, with a vertical rotation axis, upper and lower ball bearings 61 and 62 are provided, each having an inner race secured to the hollow shaft 58 and an outer race secured to one of the ends of the tubular portion 55 of the pedestal 22. The outer roll 63 of the upper ball bearing 61 is secured at the upper end of the pedestal 22 by a ring 64, and the inner race 65 of the upper ball bearing 61 is secured to the hollow shaft 58 between the shoulder 66 and a fitting 67 secured to the upper end of the shaft 58 which is threaded.

The fitting 67, which serves as a rotatable driving member for the container 23 in turn carries an inclined bearing 68, preferably a ball bearing upon which the container 23 is journaled through the supporting hub 45. The inclined bearing 68 has an axis of revolution at a slight angle to the rotation axis of the hollow shaft 58, for example at an angle of $4\frac{1}{2}$ ° in the case of the specific apparatus shown by way of illustration.

The bearing 68 has an outer race 69 secured to the rotatable, container-driving member 67 and an inner race 71 secured to a fitting 72 which is, in turn, secured to the supporting hub 45 of the container 23. In the construction, as illustrated, the fitting 72 has a threaded upwardly extending neck portion 73 and a lower base or flange portion 74, holding the inner ball-bearing race 71. The neck portion 73 extends upwardly through openings in the center of the supporting hub 45 and the center of the re-entrant bottom wall 44 of the container 23. A nut 75 and a washer 76 may be provided for clamping the parts 44 and 45 against the base 74 of the fitting 72. A locking pin 77 may be provided to prevent relative rotation between the container 23 and the fitting 72.

The lower portion of the fitting 72, that is the base 74 has spherical recess 78 to receive a spherical head 79 formed in the upper end of the control shaft 59. Diametrically extending slots 81 are formed in the base portion 74 of the fitting 72 to receive the ends of a pin 82 extending horizontally through the spherical head 79 of the control shaft 59, so as to provide a flexible connection between the shaft 59 and the container 23.

For supporting the protective cap 46 a hollow screw 83 may be provided which is threaded into an opening in the upper end of the fitting 73. An oil hole 84, closed by a spring-pressed ball 85 may be provided in the upper end of the screw 83 and the fitting 73 may be hollow, provided with oil directing holes 86 and 87 for supplying oil to the bearing 68 and to the surfaces of the spherical head 79 and the pin ends 82. Furthermore, an oil hole 88 may be provided in the rotatable driving member 67 for supplying oil to the upper pedestal bearing 63 from the oil hole 84. The clearance around the spherical head 79, and between the pin 83 and the slot 81, are such as to permit tilting motion of the parts 74 and 45 secured to the basket 23 without permitting rotation thereof around the geometrical axis 43 with respect to the vertical control shaft 59.

Preferably, a skirt 89 hanging clear of the upper and outer surfaces of the ring 64 at the upper end of the pedestal 22 is provided for protecting the upper pedestal bearing 81 from spray or drip of wash water. A similar skirt 91 may be formed at the outer edges of the container hub 45 for protecting the inclined bearing 68. As illustrated in Fig. 1, an apron 92 composed of a suitable flexible material impervious to water such as sheet rubber

for example may be fastened to the outer edges of the ring 64 and the upper edge of the wall 32 for preventing water from splashing over the wall 32 and falling upon the mechanism below the tub bottom 28.

As shown in Figs. 1 and 7 the motor 24 is arranged to drive the hollow shaft 58 rotatively through a belt 93 engaging a pulley 94 secured to the hollow shaft 58 at the lower end thereof.

As already explained in connection with Fig. 2, the upper end of the control shaft 59 is supported by reason of the spherical head 79 fitting into the spherical recess 78 in the base portion 74 of the fitting 72. For supporting the lower end of the control shaft 59 in such a manner as to permit relative rotation between the inner shaft 59 and the outer shaft 58, a bearing preferably a ball bearing 96 is provided. In the particular construction illustrated, the bearing 96 is shown as fitting within the central portion of the pulley 94. For releasingly preventing rotation of the control shaft 59 when the hollow shaft 58 is rotated, a brake drum 97 is secured to the lower end of the control shaft 59 and a brake band 98, adapted to grip the drum 97, is provided.

Suitable means are provided for bringing the control shaft 59 up to the speed of the hollow shaft 58 when the brake band 98 is not in engagement with the brake drum 97. To this end the pulley 94 may be constructed in hollow form with an inner clutch surface 99 and a plurality of centrifugal clutch dogs 101 may be pivotally mounted, as illustrated more clearly in Fig. 4, upon the web portion 102 of the brake drum 97. As illustrated, there are three clutch-dogs or fingers 101, each having an ear 103 pivotally carried by a post 104 secured in the web 102 of the brake drum 97 and having a friction pad 105 adapted to engage the inner surface 99 of the pulley 94. For preventing engagement of the clutch dogs 101 until a predetermined speed of the brake drum 97 has been reached, biasing springs 106 are preferably provided each fastened between the clutch-dogs 101 and pins 107 also secured in the web 102 of the brake drum 97.

Suitable linkage is provided for controlling the engagement of the brake band 98 with the brake drum 97. For example as illustrated in Figs. 4 and 11, a lever 108 may be provided which is pivoted to a pin 109 secured to the base plate 37 of the apparatus. One end of the brake band 98 is fastened to a pin 11 which is also secured to the base plate 37 and the other end is fastened to the pin 112 carried by the short end of the lever 108. For normally producing engagement of the brake band 98, a spring 113 is provided which is fastened at one end to a pin 114 secured to the base plate 37 and is secured at the other end to a link 115 which is in turn pivoted to the outer end of the lever 108.

Preferably, electrically controlled means are provided for releasing the brake band 98. This may take the form of a solenoid coil 116 in inductive relation with a plunger or armature 117 of laminated permeable magnetic material secured to the link 115 at the end 118 adjacent the spring 113.

For intermittently decelerating the control shaft 59 and thereby decelerating the rotary motion of the container 23 during centrifugal drying operations in response to any vibration which may occur greater than predetermined amplitude, an independent braking mechanism is preferably provided. This comprises a brake surface 119 inside the brake drum 97 and a brake finger or pad 121 extending upwardly as illustrated in Fig. 11 and adapted to engage the inner brake surface 119. Mechanism illustrated in Figs. 11 and 13 is provided for pressing the brake pad 121 against the brake surface 119 for short intervals of time in response to electrical impulses produced by vibration exceeding a predetermined minimum. Probably, this takes the form of a ratchet mechanism. For the purpose, the brake pad 121 is carried at the end of a pivotally mounted arm 122 linked by potential energy storing means such as a tension spring 123 to a rotatably

mounted plate 124 having a ratchet sector 125. For engaging the ratchet sector 125 an electrically operated ratchet 126 is provided having a solenoid operator 127 with a plunger or armature 128 secured to the ratchet 126 through a link 129. A conventional return spring 131 is preferably connected to the ratchet member 126. A rotatable plate 124 is provided with an upwardly bent ear 132 adapted to engage a shoulder 133 on the brake arm 122 for limiting the relative motion produced by the spring 123 between the brake arm 122 and the rotatable plate 124. The rotatable plate 124 is also provided with a downwardly bent ear 134 adapted to engage an adjustable screw stop 135 threaded into a post 136 secured in a supporting base plate 137, which is, in turn, secured to the main base plate 37.

Suitable means are provided for giving a slow release action to the brake pad 121. Such slow release action may be accomplished by what amounts to a rotary dash pot comprising a well 138 containing a highly viscous liquid such as a tacky oil or pitch for example and a fixedly mounted drum 141 dripping into the tacky oil 139. For fixing the drum 141 against rotation, it may be formed integrally with a disc 142 secured to a post 143 which extends downwardly through the parts 138, 122 and 124 to the base 137 to which it is secured. To prevent leakage of the fluid 139 through the opening in the bottom 144 of the well 138, a tube 140 extending upwardly from the bottom 144 and surrounding the post 143 may be provided if desired.

Ratchet teeth 145 are provided around the periphery of the bottom 144 of the well 138 in order to form a ratchet wheel. Furthermore, a click pawl 146 is pivotally secured to an ear 147 of the rotatable plate 124 and a biasing spring 148 is provided for both holding the click-pawl 146 in engagement with the ratchet teeth 145 and tending to restore or return the plate 124 to its position with the ear 134 resting against the stop 135. This action, however, is opposed by the friction of the fluid 139 between the downwardly extending drum 141 and the side wall of the well 138.

For energizing the solenoid 127 and operating the ratchet 126, whenever vibration exceeds a predetermined value, a vibration responsive switch 149 is provided which is mounted in one corner of the casing 21 as illustrated in Fig. 5.

My invention is not limited to a particular type of vibration-responsive switch. Satisfactory results may be obtained for example, by employing a pendular-type of switch such as illustrated in Fig. 10. Such a switch comprises an insulating block secured to the sidewall 20 of the tub 30 at a suitable corner of the casing 21 and carrying two conducting members 152 and 153. The conducting member 153 has a horizontally extending side portion containing a circular opening 154 and the conducting member 152 has a wire 155 suspended therefrom in such a manner as to be free to swing in all directions and adjustably carrying a bob 156 composed of conducting material. The bob 156 hangs in the opening 154.

The bob 156 may be frusto-conical in shape with the small end upward so that the higher the bob 156 is mounted on the rod 155, the closer the outer surfaces thereof will be to the edges of the opening 154, and the smaller the amount of vibration required to bring the bob 156 and the contact member 153 into the electrical contact so as to close an electrical circuit between the members 152 and 153. In order to avoid having the voltage of the normal central station supply, namely 115 volts, between the bob 156 and the contact member 153, I prefer to utilize a low-voltage circuit for operating the solenoid 127. For example, a transformer 157 may be provided having a primary winding connected to the conventional 115-volt circuit and secondary winding supplying the contact members 152 and 153 in series with the solenoid 127. The transformer 157 is a suitable step-down transformer such as a bell-ringing transformer, for

example, reducing the secondary voltage to a suitable low value such as 8, 16 or 24 volts, for example.

As illustrated in Fig. 7, there is a pump 158 driven through the belt 93 by the motor 24. As shown in Fig. 8, the pump 158 is preferably of the vane type so as to draw relatively little power from the motor 24, and has a pair of vanes 159 drawing water from an inlet opening 161 and discharging it through a passageway 162. The inlet 161 is connected through a length of hose or tubing 163 to an opening in the tub bottom 28. The opening is not visible in Fig. 1, since it is assumed to be in front of the plane along which the sectional view of Fig. 1 is taken.

A two-way valve 164 is provided in the discharge 15 passageway 162 for connecting the pump discharge 162 either to a drain hose 165 or to a recirculating discharge head 166. The two-way valve 164 comprises valve discs 167 and 168 adapted to cooperate with inclined valve seats 169 and 171, respectively. The valve discs 167 20 and 168 are carried by a lever 172 secured to a rotatable shaft 173 extending through the pump casing. The recirculating discharge head 166 has twin outlets to which lengths of hose 174 and 175 are connected, which are in turn connected at their upper ends to recirculating discharge spouts 36 as illustrated in Figs. 1 and 5.

For enabling the two-way valve 164 to be electrically operated, a solenoid 176 is provided having an armature or plunger 177 resiliently biased by a spring 178 and connected through a yielding linkage 179 to a crank 181 keyed or pinned to the control shaft 173 of the valve 164. The yielding connection 179 comprises a connecting rod 182, a crank pin 183 having an opening receiving the connecting rod 182, a spring 184 surrounding the rod 182, and a collar 185. The crank pin 183 is slidable along the rod 182 and the spring 184 fits between the crank 183 and the collar 185.

The linkage is so connected that the spring 178 holds the valve disc 167 upward against the valve seat 169 normally so that the drain through the opening 165 is opened except when the solenoid coil 176 is energized, whereupon the valve disc 168 is held against the lower seat 171 so as to cause the recirculation of water.

In order to proportion the rate of flow of water recirculated through the nozzles 36 into the clothes container 23 to the discharge through the drain holes 47, 49, 51 etc., means are provided for controlling the supply of water to the nozzles 36 or the rate of flow of water. The arrangement is such that if a full stream of water is not issuing from the recirculating nozzles 36, additional water will be supplied through the supply nozzle 35.

Preferably, a float switch, designated generally by the reference numeral 201, in Figs. 5 and 12 is provided in the lower portion of the tub 30 above the bottom 28. The float switch 201 may comprise a float 202 composed of a light material such as cork or the like secured to an arm 203 in the form of a thin rod 203 protruding through an opening in the side wall of the tub for operating a micro-switch 204. The micro-switch 204 is supported in one corner of the casing 21 by a suitable bracket 205, and is provided with an operating arm 206 adapted to be engaged by the arm 203 of the float 202. For sealing the wall 20 where the rod 203 extends through it, a grommet 207 composed of rubber or rubber-like material is employed, and the grommet serves also as a flexible hinge and a frictional holding means for the rod 203.

Although my invention is not limited thereto, in the specific arrangement illustrated, the micro-switch 204 is so arranged as to be normally open, and is closed whenever the float 202 fails to lift the rod 203 against the operating arm 206 of the micro-switch 204.

As will be explained more in detail, hereinafter, the micro-switch 204 is connected in series with a valve operating solenoid for controlling supply of either hot wash water or warm rinse water through the supply nozzle 35.

The water supply spout 35 may be connected to a

source of hot or warm tap water through a line such as a flexible hose line 209, shown in Figs. 5 and 7. An electrically operated valve unit 211 is provided having a single outlet 212 connected to the supply-water-hose-line 209, and having two separate inlets 213 and 214, including separate solenoid valves 215 and 216 (shown encased) for controlling the supply water through the lines 213 and 214. It is to be understood that suitable thermostatic mixing devices, known to those skilled in the art, may be provided for causing hot and cold tap water to be mixed in the proper proportions to supply hot washing water of the temperature of approximately 150°, for example, to the input line 213 and similarly a suitable mixing arrangement may be provided for supplying somewhat cooler, but slightly warm rinse water at a temperature of approximately 100°, for example, to the input line 214.

The ribs 42 are preferably L-shaped, each comprising an inclined leg portion 217 and a substantially horizontal, but slightly sloping scoop foot portion 218, as illustrated in Figs. 1 and 3. As illustrated in Fig. 1 the leg portion 217 lies along the nearly upright, but very slightly inclined side surface of the container 23 and the scoop foot portion 218 lies radially along the inner surface of the bottom of the container 23. The foot 218 preferably has a sloping approach surface 219 similar to the "face" of a "mashie." The front surface 219 of the foot portion 218 lies in the same continuous plane as the front surface 221 of the leg portion 218. Sections taken through the rib 42 such as a section A—A represented in Fig. 3—A are substantially triangular. In order to give action similar to that of a wash board, grooves 222 and 223 are preferably formed in the leg portion near the inner edge 224 and parallel thereto in order to form the edge 224 into a bead similar to the ribs on a washboard. The front surface 221 of the rib 42 is preferably inclined at an angle to the geometric axis 43 of the container 23. It will be understood, that my invention is not limited to use of ribs of the precise form illustrated or to a specific angle of inclination of mounting. However, I have found the arrangements specifically disclosed to give satisfactory operation with an inclination angle of 38°.

My invention is not limited to a specific type of apparatus for the timer 26. Preferably, however, for the sake of precision in the operation of the timer and precision in the fixing of the intervals, since the time intervals involved are relatively short, I employ a timer of the multiple-cam type, including a plurality of separate cams 225, each actuating the protruding operating pin or button of one of the group of conventional micro-switches, 226, 227, 228, 229, 230, 231 and 232. The micro-switches 226 to 232, inclusive, are of the type well known to those skilled in the art having protruding pins (not shown) which are moved in when the appropriate one of the cams 225 reaches the angular position in which the radius of the cam is sufficient to depress the micro-switch operating pin. Such a timer includes a constant speed driving motor such as a synchronous motor 233, not visible in Fig. 1, having a drive shaft 235 carrying the cams 225 and also extending upwardly to the manual starting knob 27. The latter is secured to the upper end of the cam shaft 235 for permitting manual starting and also permitting manual advancement of the cam to a more advanced position if desired.

The electric circuit arrangement of the electric timer 26 and the electrical apparatus controlled thereby is represented schematically in Fig. 14. The contacts of the micro-switches 226 and 232, inclusive, are indicated schematically in Fig. 14 by corresponding reference numerals primed. The driving motor of the timer 26 is 70 represented in Fig. 14 by a circle 233.

As indicated in Fig. 14, a source of electrical current from a power supply system is utilized having conductors 236 and 237, the latter of which is designated as a return conductor as a matter of convenience in designat-

ing the various branch circuits of the apparatus. During such times as the various contacts may be closed, circuits are formed as follows:

From the conductor 236 through timer contacts 232', 5 the timer motor 233, and back to the return conductor 237; from the conductor 236 through the timer contacts 231', through the drain solenoid 176, back to the return conductor 237; from the conductor 236 through the timer contacts 230', the hot water supply valve solenoid 215 10 and Sylphon switch 204 to the return conductor 237; from the conductor 236 through the timer contacts 224', the warm water supply valve solenoid 216, the Sylphon switch contact 204, back to the return conductor 237; from the conductor 236 through the timer contacts 228' and the washer brake releasing solenoid 116, back to the return conductor 237; also from the conductor 236 through the timer contact 227' and the washer brake releasing solenoid 116, to the return conductor 237; and from the conductor 236 through the timer contacts 226', and the washing machine driving motor 24, back to the return conductor 237. A branch circuit is also formed paralleling that of the motor 24 including the vibration damper brake operating solenoid 127. The latter branch circuit exists however only when the switch 149 is closed. Preferably, 25 a lamp 238 is provided which may be connected in parallel with the timer motor 233 as to be illuminated whenever the timer 26 is turned on.

The circuit diagram of Fig. 14 is merely schematic and does not serve to indicate the order in which the various 30 timer contacts 226' and 232' inclusive are closed or make contact. In order that the contacts will be closed in the desired succession, the cams 225 shown in Fig. 1 are arranged in different angular positions on the shaft 235 to produce circuit closing in the successive order indicated 35 in Fig. 6, and are appropriately shaped to produce closing of contacts for the time duration indicated in Fig. 6. Such cam shaping is known to those skilled in the art and thus has not been specifically illustrated. The significance of Fig. 6 will be explained more in detail hereinafter in 40 connection with explanation of the manner of operation of the apparatus.

As already explained, the casing 21 is provided with four feet 39, one in each of the four corners of the base 37. As shown in Fig. 1, the feet 39 serve also to fasten 45 the legs 57 of the pedestal 22 to the base 37. Preferably slide cups 239 are provided under each of the feet 39 in order to guard against possible transmission of vibration from the casing 21 to the floor 38 and to prevent "crawling" of the washing machine in the event of momentary 50 excessive vibration. As previously mentioned also one of the feet 39' is mounted in a self-leveler or hydraulic stabilizer 41. With the respect to the manner in which the feet rest in the slide cups 239, however, the foot 39' is identical with the other feet 39. The detailed construction is shown in the enlarged sectional view of Fig. 8, 55 showing also the hydraulic stabilizer 41.

Preferably the slide cups 239 are joined by web framework or a plate 241 to insure that the four cups 239 will be spaced accurately at the four corners of a square so as to coincide with the positions of the feet 39 or 39' or the plate 37. Preferably, the top surface 242 of the cup 239 is concave, e. g. in the shape of a portion of a hollow sphere so that the feet 39 or 39' tend to slide back to the bottom of the spherical surface 242. A drop of grease may be placed under each foot in order to insure a minimum of friction or a high degree of side-wise slippage freedom.

The hydraulic stabilizer shown at 41 comprises a hollow screw 249, a cylinder 251, a hollow cap 252, a lower spring-pressed piston 253, an upper spring-pressed piston 254, and a flow restrictor 255. The pistons 253 and 254 are slidable in the cylinder 251 which is filled with a suitable fluid such as oil. The foot 39' has a shank 256 slidable in the hollow screw 249 and preferably the lower piston 253 is integral with the shank.

256 of the foot 39'. The hollow member 249 is secured in a suitable manner to the pedestal leg 57 and the base 37. In the specific arrangement illustrated, the hollow member 249 is a screw threaded into the pedestal leg 57, passes through an opening in the base 37, and is provided with a nut 258 for securing the base 37 and the screw 249. The ends of the cylinder 251 are threaded into the hollow head of the screw 249 and into the cap 252. Preferably, packing heads or the like 259 and 261 are provided for packing the pistons 253 and 254 respectively. A compression spring 262 located within the hollow cap 252 between the upper end of the cap 252 and the piston 254 is provided for urging the flow of fluid from the space in the cylinder 251 above the flow restrictor 255 through the restrictor 255 into the space above the piston 253 for yieldably urging the foot 39' downwardly into contact with cup 239. A weaker compression spring 263 is provided for limiting the downward extensibility of the foot 39'.

The flow restrictor 255 comprises a transverse wall 20 formed in the cylinder 251 having an orifice 264. Preferably the orifice 264 has a relatively large diameter portion 265 which extends nearly through the transverse wall 255 and only a portion of relatively short length constitutes the actual flow restricting orifice 264.

To assist in filling the chambers 266 and 267 with oil or other suitable fluid and draining air from the chambers as well as draining excess fluid, bleed holes 268 and 269, respectively, are provided. Screws or the like 271 are provided for plugging the bleed holes 268 and 269 after the chambers 266 and 267 have been filled solely with the desired quantity of oil or other fluid.

A timer diagram shown in Fig. 6 indicates diagrammatically the shaping of the cams 225 of the timer 26 by indicating the time periods during which the respective micro-switches 226 and 232 are closed. As indicated diagrammatically in Fig. 6 and shown in the circuit diagram of Fig. 14, the timer switches 230 and 224 controlling the supply of water are subject to the control also of the Syphon switch 204 shown in Figs. 5 and 12, operated by the Syphon 202. Furthermore, as indicated diagrammatically in Fig. 6, the effect of the timer switches 227 and 228 controlling extracting and rinsing operations are also subject to modification by the pendular vibration-responsive switch 149 in a manner which will be brought out more clearly hereinafter.

The first operation in using the illustrated apparatus obviously is to place the articles to be washed such as clothes, for example, in the container 23 shown in Fig. 1 and Fig. 5. The starting knob 27 is then turned manually in the starting direction, for example clockwise. A very slight turn causes the switch contact 232 to close which energizes the driving motor 233 of the timer 26 and from this point on the cams 225 of the timer 26 are automatically driven to carry out the timing operations. As indicated by the continuous heavy line 272 in the chart of Fig. 6, the shape of the timer cam controlling the switch contacts 232 is such that the contacts are closed one minute before the time intended for the main motor 24 to start and remain closed thereafter for a period of twenty-two and one-quarter minutes. That is, the switch contacts 232 remain closed, from the time minus one minute to the time twenty-one and one-quarter being a total of twenty-two and one-quarter minutes.

One quarter of a minute after the switch contacts 232 have closed, the switch contacts 230, controlling the supply of hot water, are closed as a result of the shaping of the cam controlling the switch contacts 230. Thus, as illustrated in the diagram of Fig. 6, the hot water supply is opened at time minus three-quarters minute. Referring to Fig. 14, provided the float switch 204 is closed, the hot water supply valve solenoid 215 is energized by the closing of the switch 230, and water begins to flow into the container 23 through the supply nozzle 35. Obviously, the switch 204 will be closed at the commence-

ment of operations before any water has flowed into the container 23, and drained into the tub 30 to lift the float and open the switch 204. Thus the water supply is started before the main motor 24 is started.

One-quarter of a minute later, namely at the time minus one-half minute as indicated in the diagram of Fig. 6, the switch 231 is closed to actuate the drain operating solenoid 176 and close the drain 165. This allows the hot wash water to remain in the tub 28 and to be recirculated by the pump 158 through the recirculating nozzles 36 as soon as the motor 24 starts. Soap powder or solution may then be admitted to the tub 30. At zero time in the diagram, the switch 226 is closed, energizing the main motor 24, which starts the pump 158 in operation, and also rotates the pulley 94 driving the hollow shaft 58 shown in Fig. 2. Owing to the fact that the brake drum 97 is gripped by the brake band 98 in consequence of the force of the spring 113 shown in Fig. 11, the center or control shaft 59 is prevented from rotating, the inclined-bearing-carrying, rotatable driving member 67 is caused to rotate while the container 23 is prevented from rotating about its geometric axis 43 by the stationary condition of the shaft 59 linked to the container 23 through the slotted member 81 and the pins 32. This produces a rotatively progressing vertically reciprocatory motion of the lower surfaces of the container 23 which will be discussed more in detail hereinafter. At this point it will be sufficient to point out that this produces the washing action upon the articles placed in the container 23. As indicated by the extent of the dotted line 273 in Fig. 6, the hot water supply valve solenoid 215 controlled by the switch 230 remains energized until the time seven minutes. For the greater portion of this time, indicated by the dotting of the line 273, the supply valve is not opened owing to the fact that the switch 204 is open as soon as sufficient water has been supplied to the tub 30 which usually takes place during the preparatory three-quarter minute period from the time minus three-quarters to zero minutes.

The automatic control of the delivery of water to the container 23 through the supply spout 35 is in part dependent on the quantity of clothes in the container 23. The water required to saturate the clothes is retained in the container 23 while sufficient water is accumulating in the tub 30 to permit a full stream to be delivered through the spouts 36.

One quarter of a minute before the end of the seven-minute washing period, the drain control switch 231 opens, causing the drain 165 to open and allow water to commence to be withdrawn from the tube 30. Right at the end of the seven minute period, the switch 227 is closed actuating the extractor solenoid 116 to release the brake band 98 as indicated in Fig. 11. This allows the center shaft or control shaft 59 shown in Fig. 2 to rotate, permitting the container 23 also to rotate, and to come up to speed gradually for centrifugal drying purposes. Owing to the inertia and the continual change of oscillation velocity of the container 23 necessary for carrying out the rotatively progressing reciprocatory motion through the inclined bearing 68, there is a tendency for dynamic coupling between the shafts 58 and 59 so that the shaft 59 and the container 23 tend to come up to a speed approaching that of the tubular shaft 58. In practice the speed may attain approximately one-half the speed of the shaft 58. This speed however is sufficient to throw out the clutch dogs 101 shown in Fig. 4 so that an additional coupling between the shaft 58 and 59 is produced, namely, a slip clutch effect due to the frictional engagement of the clutch shoes 105 with the inner pulley surface 99. The control shaft 59 is brought up to the full speed of the tubular shaft 58 so long as no braking effect is applied to the drum 97. Thus by utilizing but one single-speed motor 24, the container 23 may alternatively be vibrated or rotated with the same number of oscillations per minute in one case, or revolutions

per minute in the other case, depending upon whether the washing or the drying operations are to be produced. Furthermore, no more driving power is required for drying than for washing.

As indicated in Fig. 6, the extracting or drying operation continues for a period of two minutes during which the switch 227 remains closed. However, at three-quarters of one minute before the end of this period, namely at the time eight and one-quarter minutes indicated by the diagram, the switch contact 229 has closed causing the warm supply water solenoid 216 to be energized and thereby causing warm rinse water to flow into the container 23 through the supply nozzle 35.

One-quarter minute later the drain control switch 231 closes to cause the warm rinse water to be retained in the tub 28 and to permit recirculation of warm rinse water through articles in the container 23. When the full stream is obtained from the recirculating nozzles 35, the Sylphon switch 204 cuts off the warm rinse water, as during the washing period.

At the time nine minutes, the switch 227 opens causing the extractor controlling brake band 98 to be reengaged with the brake drum 97 by the force of the spring 113.

The container 23 at the time nine minutes resumes its washing action except that a fresh supply of clean warm rinse water is recirculated instead of the hot soapy water utilized during the first period, and consequently the clothes are being rinsed instead of washed although the same mechanical action is being employed. The rinsing action continues for a period of about three minutes. One-quarter of a minute before the end of this period, however, namely at the time eleven and three-quarters minutes the drain control switch 231 re-opens allowing the rinse water to be drained away for a period of one-quarter minute. Whereupon, the extractor switch 227 again closes releasing the brake 98 and allowing the center shaft 59 as well as the container 23 to be rotated as previously explained at the full speed of the tubular shaft 58 for extracting or centrifugal drying purposes. The invention is, of course, not limited to a predetermined number of extracting and rinsing periods, however, in the specific time diagram illustrated there is a second extracting period continuing for about two minutes followed by another rinsing period continuing for about three minutes. As indicated in the diagram at the time thirteen and one-quarter minutes, the warm water supply switch recloses, and, at the time thirteen and one-half minutes the drain switch 231 recloses for enabling the recirculation of rinse water during the succeeding rinse period.

At the time sixteen and one-quarter minutes the drain switch reopens and remains open for the entire remainder of the operating cycle of the timer, assuming that only two rinse periods are to be employed. Then at the time sixteen and one-half minutes the warm water supply switch 229 reopens the extractor switch 227 recloses to commence extracting without rinse water for the purpose of drying the clothes sufficiently for ironing. Preferably, however, after a period of time sufficient for the bulk of the water to be extracted, for example at the time seventeen and one-half minutes, the extractor brake band is momentarily reengaged with the brake drum 97 as indicated by the opening of the extractor switch contacts 227. These contacts remain open for about eight seconds before the parallel set of extractor switch contacts 228 is closed for resuming the extraction or centrifugal drying operation which continues for the remainder of the period of about four and one-half minutes until the time twenty-one minutes. During the eight second interval between the opening of the switch contacts 227 and the closing of the contacts 228, the articles in the container are subjected to the washing action without water so that the clothes which may be packed against the outer walls of the con-

tainer 23 are shaken loose or fluffed. Since by this time the bulk of the water has been removed, they do not repack during the remainder of the extracting operation produced by the closing of the switch contacts 228.

At the time twenty-one and one-quarter minutes the switch contacts 232 reopen de-energizing the timer motor 233 and the cycle comes to a close. The main motor 24 having been de-energized at the time twenty-one minutes by the opening of the main motor switch 226.

Upon removal of the articles from the container 23 and the refilling with other articles to be washed, the cycle just explained may be repeated.

Although a specific operating cycle has been described, my invention is not limited to this specific cycle. For example, in an alternative cycle which I have found advantageous, there is a fluffing period at the end of the drying cycle. The container 23 is operated with the washing action for about one-half minute after end of the drying cycle, that is, after the extracting is completed by spinning. This is accomplished by setting the extractor switch contacts 228 to open thirty seconds before the main motor switch contacts 226 open. Accordingly washing action is resumed for thirty seconds as indicated by the dotted portion at the right hand end of the line 227 in Fig. 6. This fluffing period shakes up the clothes and separates them so that they are not matted into a doughnut and the clothes may therefore be removed readily from the container 23. The hereinbefore described previous fluffing period of eight seconds, interposed intermediate the extracting period, serves as a preliminary fluffing period to minimize packing and the fluffing period at the end of the drying cycle finally shakes down the clothes for ease in removal from the machine. If the previous fluffing period is not employed the switch contacts 228 may be omitted and the contacts 227 are set to remain closed until thirty seconds before the contacts 226 open.

During the extracting or centrifugal drying action when the tubular shaft 58 and the control shaft 59 are rotating together to cause rotation at the same speed of the container 23 about the axis of the shafts 58 and 59, there may be a possibility of unbalance of the load held in the container 23 which would tend to cause vibration. Such an unbalance might occur, for example, in case a single bulky article were placed in the container 23 so that notwithstanding the redistribution ordinarily produced during the washing action, a redistribution of the load in the basket 23 to balance the load could not occur in this case.

In this case, while the article or articles held in the basket or container 23 are still quite wet the unbalance may be relatively large. Consequently, the pendulum 153 of the vibration-responsive switch 149 would be caused to bob against the guard 156 and establish a circuit through lines 157, 151, bracket 152, rod 155 and solenoid 127. This will energize the solenoid 127 shown in Fig. 11 drawing in the ratchet 126 and causing the plate 124 to be notched up on the ratchet wheel 145. This action will tension the spring 123 and cause the brake pad 121 to engage the inner surface 119 of the brake drum 97. This will give a temporary drag to the rotation of the shaft 59 causing the centrifugal clutch dogs 101 to slip and prevent excessive vibration of the load in the container 23 by reducing the rotation speed. As the container continues to rotate at the reduced speed, water will continue to be expelled therefrom centrifugally, and the unbalance will be reduced. However, if the unbalance should continue, the pendulum 153 will continue to vibrate, causing additional contacts, each time energizing the solenoid 127. Each time such vibration takes place, the circuit through 153—156 will be closed once for each vibrating movement in one direction, the solenoid 127 will be energized

once and the plate 125 will be notched up an additional amount causing further tensioning of the spring 123 and tighter engagement of the brake pad 121 against the inner brake surface 119 of the brake drum 97. The ratchet wheel 145, gradually gives however rotating to the left against the friction of the tacky fluid 139 on the wall 138 so that gradually the brake pad 121 is released again. The time duration of application of the brake pad 121 obviously depends upon the severity of the vibration which determines the extent to which the plate 124 has been turned. By the time the brake pad 121 has been released, sufficient water has been expelled from the load in the container 23 to overcome the excessive unbalance and the container 23 may then again be brought up to full speed which takes place automatically and continues to the end of the cycle determined by the diagram of Fig. 6.

It will be observed that during the washing action when the control shaft 59 is held stationary by the brake band 98 acting on the brake drum 97, the driving member 67 rotates the tilted bearing 68 in which the supporting hub 45 for the container 23 is journaled. Consequently, the geometric axis 43 of the container 23 is continuously tilted, being tilted in a different direction progressively moving around the axis of the shaft 59. For example, a point in the geometric axis 43 of the container 23 above the center of mass thereof such as the oil hole 84, for example, rotates around the axis of the shaft 59 whereas the container 23 itself is prevented from rotating about its geometric axis 43 by the reason of the engagement of the slot 81 with the pins 82 of the stationary shaft 59. In consequence of this action, any given point in the lower surface of the container 23 is being caused to rise and fall or to reciprocate vertically at a rate which in the embodiment illustrated corresponds to the rate of revolution of the hollow shaft 58. Thus here any particular point in the bottom surface of the container 23 rises and falls as many times per minute as the tubular shaft 58 rotates per minute. Different portions of the mass of water and articles in the container 23 are reciprocated in a vertical direction with progressively different phase around the center.

My invention is obviously not limited to particular dimensions, but I have found that an angle of tilt of $4\frac{1}{2}^\circ$ for the axis of relative rotation of the bearing 68, which gives a maximum movement of 9° , serves to produce satisfactory washing action with a container 23 having an 11 inch radius. With the shaft 58, such an arrangement revolving at a speed from 500 to 600 R. P. M. for example, the vertical component of motion of the bottom surface of the container 23 continuously varies in velocity, with accelerations or decelerations reaching peak values exceeding the acceleration of gravity. Consequently, during a portion of each oscillation each portion of the bottom surface of the container 23 near its periphery drops more rapidly than the articles supported by such portion of the container 23.

Air pockets are thereby formed within the clothes or other articles and above the bottom surface of the container 23. As any portion of the container 23 reverses its downward acceleration, such portion of the bottom surface of the container 23 drives air and water through the clothes and spans the bottom surface of the mass of articles in the container 23, thus causing jets and geysers of soap water or other cleansing liquid such as dry cleaner's solvent to be forced through the mass of articles in the container 23 and causing dirt to be loosened. The mass of clothes or other flexible fabric articles are alternately squeezed together and opened out in vertical direction by this action to aid the cleansing effect.

It will be observed that the vibratory motion of the bottom wall of the container 23, especially the vertical component thereof, has a very small amplitude, only about one and three-quarters inches at the outer periphery of the container 23, in the illustrative example given.

The frequency of vibration is very high, at least three hundred oscillations per minute, and preferably over 500 oscillations per minute, for example, 600 oscillations per minute. In the illustrative case the outer periphery of the bottom wall of the container is caused to drop one and three-quarters inches in one-twentieth of a second. The clothes and water at the outer periphery of the container 23, however, could fall a maximum of less than one-half inch during this time if falling freely from rest so as to be acted upon by the full force of gravity.

Such rapidity of pulsation of the mass of articles to be washed and the way in which they are manipulated enables adequate cleansing to be obtained in the very short washing period mentioned and accordingly shortens the complete washing, rinsing and drying cycle.

Owing to the control of liquid supply, relatively little water or other cleansing liquid, is allowed to remain in the container 23—that is to say, the flow of water into the container through the recirculating nozzles 35, about ten gallons per minute in the specific case described for illustration, is proportioned to the amount of water draining out through the rows of holes 47 to 53 inclusive. For example, with a load of six pounds dry weight of clothes in the container 23 approximately six gallons of water are retained within the system. Only enough water is retained in the container 23 for the clothes to be slippery and slide around freely and mix with water and air, but not enough for the clothes to be immersed. For example, in a normal washing load there may be five inches of clothes and water in the container 23, but if the container should be stopped suddenly, before any water had run out and before any more had run in there would be only one and one-half or two inches of water in the container.

The component of vertical reciprocatory motion of a given portion of the container 23 has a different time phase from the reciprocatory motion of any other portion of the container. Thus the time phase of the reciprocation or the time instant at which any particular point around the periphery of the container reaches its highest point or its lowest point is progressively later around the center of the container 23. Circumferential progressive inclination is imparted to the bottom wall of the container 23. This action may also be described as rotatively progressing reciprocatory motion or vertical reciprocatory motion of different portions of the container which varies progressively in phase around the center of the container. It may also be called rotatively progressing rocking movement or see-saw motion, since at any instant points on one side of the container 23 are moving in the opposite vertical direction to points on the opposite side of the container. As a result of this motion of the container a substantially vertical jiggling action is imparted to clothes and water disposed along the bottom wall of the container 23 and this jiggling action progresses circumferentially.

But for the ribs 42, the slippery mass of clothes in the container 23 would tend to be slued around at the outer lower edge 48 of the container 23. The ribs retard this motion, but do not entirely prevent it. The ribs 42 each execute an elliptical movement. With each oscillation of a rib the foot portion 218 comes down under the wet mass of clothes like a mäshie lifting a golfball. With the shaft 58 rotating at a velocity of approximately 600 R. P. M. representing a vertical oscillation each tenth of a second, the articles in the container 23 may be caused to travel around once in twenty seconds, thus producing a shifting action for distributing the contents of the container 23. Owing to the fact that the face 219 and the surface 221 of the rib 42 (referring to Figs. 1 and 3) are inclined, there is a tendency for the portions of the container contents toward the outside of the container to be driven upward. This results in what may be described as roll-over motion or redistributing action. In this component of motion, the clothes at the outer

periphery of the container 23 tend to rise, and then move toward the center and work down again near the center of the container 23, whereupon they slide outward again along the lower surface thereof. This roll-over motion may take place, for example, once in six or eight seconds. Thus there are three components of force acting and of motion of the articles within the container 23. One component is the vertical reciprocatory component or the oscillatory component which takes place each one-tenth of one second in case of shaft rotation of 600 R. P. M.; the second component which is a slower action than the vertical component of motion is the roll-over component which may take place once in six to eight seconds; and the third component, which is still slower is the circumferential component of motion around the container which may take place in twenty seconds. These components of motion take place at sufficient speed to cause a milling action of the mass of articles in the container 23, and a boiling action in the water and clothes disposed in the container. The action of the container is such that an eight-pound load of clothes placed in one side of the container will be distributed within two minutes to almost perfect balance.

The rate of the vertical reciprocatory or oscillatory component is obviously determined by the rotative speed of the tubular shaft 58. However, the rate of velocity of the roll-over component of motion and the circumferential component of motion depend upon the arrangement of the rib 42, such as the amount of scooping action and the angle at which the inclined leg 217 of the rib 42 is mounted in the container 23. I have found that these components of motion, especially the roll-over component of motion should be fast enough to prevent the clothes from ballooning or becoming excessively filled with air, and also slow enough so as not to cause the clothes to twist or tangle. Adequate water supply is also requisite to prevent twisting or tangling of the clothes in the container 23. The action of the articles in the container 23 during washing may be observed by reason of the fact that the cover 34 is transparent and the interior of the container 23 is illuminated by the lamp 238 which is mounted outside a transparent guard or shield 274.

The container 23 is mounted just high enough to provide clearance above the tub well 31 over the motor 24, so that the center of gravity of the entire machine is kept relatively low.

Very little water is required for washing since the clothes are not immersed and merely a small quantity of water in the tub 30 in addition to that absorbed by the clothes is sufficient to provide water for continuous recirculation. Consequently the machine is highly economical of water, especially important when special sources of soft water are employed, and the machine is also economical of fuel for heating water and economical of soap.

The reciprocatory motion of the container 23 produces upward and downward forces, simultaneously of the same magnitude, by reason of the fact that one side of the container is being moved upward, while the other side is being moved downward, and the acceleration and the velocity of upward motion are always equal to the acceleration and velocity of the downward motion. For this reason there is relatively little tendency for a vertical component of vibration to be transmitted to the floor 38. This freedom from vibration transmission is aided, also, by the fact that the legs 57 for the pedestal 22 are very slightly resilient with respect to up and down motion, but relatively stiff with respect to bending motion of the pedestal 22, the base plate 37 being relatively massive. The freedom from vertical component of vibration effects is further aided by reason of the fact that the casing 21 stands very firmly upon the floor or ground 38 regardless of the smoothness of the floor 38 by reason

of the fact that the fourth foot 39' is mounted in the hydraulic stabilizer 41.

Referring to Fig. 8, the spring 262 tends to expel oil from above the flow restrictor 255 through the orifice 264 into the space below the restrictor 255, thus moving the foot 39' downward to make firm engagement with the surface 242 of the cup 239.

In the event that the foot 39' should have been placed upon a high spot in the floor 38, the additional weight upon this foot will force fluid back upward through the restrictor 255 and compress the spring 262 slightly. As far as any gradual movements are concerned, the spring 262 allows the foot 39' to be brought exactly in the required position, and the spring 262 serves to yield in case the apparatus should be moved to a different position on the floor in which a different relative position of the foot 39' would be required. However, the orifice 264 in the restrictor 255 is so small, e. g. 0.010 inch in diameter, as to prevent rapid movement of the foot 39', so that any vibratory effects cannot cause any relative motion of the foot 39' with respect to the hollow screw 249, and consequently a very firm engagement with the floor is produced.

This firm engagement with the floor is helpful also during the extraction or centrifugal drying action when there might be a tendency for sidewise vibration in case of unbalance of articles within the container 23. There may then be a tendency for the casing 21 to slide back and forth sidewise at the rate of vibration corresponding to rotation speed 600 R. P. M. of the tubular shaft 58.

However, the anti-friction lower surface of the foot 39 or 39' resting upon the anti-friction surface 242 in the slide cup 239 permits this sidewise motion to take place without causing any movement of the slide cups 239 upon the floor 38. This movement will be found to very minute and so long as no opposing friction is presented to it, the feet 39 or 39' may be allowed to vibrate sidewise very slightly without causing any crawling or walking action. If the feet rested directly upon the floor 38 so as to introduce friction effects which might be unequal on different feet, there might be a tendency for the casing 21 to crawl or move about on the floor 38.

In the arrangement illustrated in Figs. 1 and 8, there is a plate or web 241 for locating four slide cups 239 resting directly upon the floor 38, and the entire washing machine in its casing 21 is adapted to be supported by the feet 39 and 39'. In the event of an unbalanced overload causing any vibration during extraction, slight vibration of the casing 21 may be perceptible to the touch as the feet 39 slide sidewise in the cups 239. However, the invention is not limited to the specific arrangement as illustrated in Figs. 1 and 8 and heretofore described. In practice, I prefer to mount the carriage for the tub 30 as well as the tub 30 and the associated apparatus within a cabinet or separate outer casing 301, e. g., as illustrated in Fig. 15. The casing 301 is provided with a lower plate 302 in the form of a hollow square corresponding to the web 241 shown in Fig. 1, and carrying the four slide cups 239 within the casing 301. Instead of a solid base plate 37 for the washing machine carriage as shown in Fig. 1, in the arrangement of Fig. 15, preferably a base plate 303 is provided having the center portion 304 cut away. The carriage for the tub 30 and the other operating mechanism comprises the base plate 303, the legs 57, the feet 39 and 39' secured thereto so as to rest upon the slide cups 239, and suitable means such as angle iron brackets 305 or the like provided for supporting the tub 30 upon the base plate 303.

In order to cause the casing 301 to rest firmly upon the floor 38, regardless of the flatness of the floor 38, adjustable feet are preferably provided for the casing 301 comprising elongated nuts 281 threaded upon bolts or screws 282 extending through the web or plate member 302 forming the base of the case 301.

The tub 30, as in the arrangement in Fig. 1, is substantially circular whereas the casing 301 is rectangular. The casing 301 is sufficiently larger than the tub 30 to provide a clearance 306 between them. In this manner sidewise freedom of motion is allowed the feet 39 and 39' together with the tub 30 and the carriage therefore without contacting or transmitting vibration to the casing 301, so that the presence or absence of unbalance which may cause some slight sidewise vibration or sway of the internal apparatus is not perceptible even by touching the outer casing 301.

In the arrangement of 15 there is a splash guard 275, formed integrally with the cabinet top 276. The splash guard 274 is to divert into the tub 30 any liquid which may splash from the container 23. Preferably, however, a flexible seal 307 is provided between the splash guard 274 and the top 308 of the tub 30. The seal 307 comprises an endless band of flexible elastic material such as sheet rubber of the weight and characteristics employed in automobile inner tubes, for example, having a normal unstretched circumference somewhat less than the circumference of the tub 30. The upper rim of the tub 30 is preferably double-flared as shown so as to provide a groove 309 and a top edge 311 rounded for protecting the rubber band 307. The band 307 is stretched sufficiently to fit over the edge 311, and a ring or cable 312 is fastened around the edge 308 in the groove 309 to secure the seal or band 307.

The splash guard 275 in the embodiment of Fig. 15 may be composed of metal formed integrally with the top 276 of the casing 301. In this case, a window 277 is provided for admitting light from the lamp 238 to the interior of the article container 23. The window 277 may be covered with a suitable translucent or transparent material such as plastic, for example, Lucite.

In order to provide readily visible indications of the point in the cycle of operations which the apparatus has reached, an illuminated dial 278 may be secured to the rotatable shaft 235 of the clockwork mechanism and switch-operating cams 225. The dial 278 is in the form of a flat truncated cone, having a plurality of slits 279 cut in the conical surface. The slits are either open or filled with translucent material such as a suitable plastic, and are positioned to indicate the time divisions corresponding to the ends of various time periods in the schedule represented in Fig. 6. A light-transmitting opening is provided in the portion of the casing top 276 under the dial 278 in order to admit light to the slits 279. A suitable index may be marked upon the top surface of casing top 276 at the edge of the dial 278, or if desired, a slit may also be cut in the top 276 to form an illuminated index.

In connection with Figs. 1 and 11 I have described an arrangement which I have found satisfactory for preventing excessive unbalance of the articles which may be placed in the container 23 from causing vibration when the container is rotated for extraction or drying of the articles in the container 23. However, my invention is not limited to the specific arrangement already described. Preferably, as illustrated in Fig. 15, for example, I provide a simple braking mechanism with relatively movable parts adapted to contact in response to vibration. One part is secured to a stationary element, such as the casing 301, and the other part rotates with the shaft 59 which is the control shaft of the washing apparatus, so that immediate braking takes place in the event that the mechanism carried by the carriage mounted on the base plate 303 is caused to sway or vibrate with sidewise movement.

The vibration-preventing braking mechanism for the apparatus of Fig. 15 comprises a pair of concentric brake drums with a small clearance between confronting surfaces. In the specific arrangement illustrated, the rotatable brake surface is the inner-cylindrical surface 119 of

the brake drum 97 and the stationary brake surface is on the outside of a fixed drum 314. The stationary drum 314 is secured by suitable means such as strips 315 to the lower plate 302 of the casing 301. Preferably, a brake band 316 is riveted, cemented or otherwise secured to one of the confronting brake surfaces, for example, to the drum 314. A relatively small clearance 317 of the order $\frac{3}{16}$ of an inch, for example, is provided between the outer surface of the brake band 316 and the inner surface 119 of the brake drum 97, so that, although the drums 314 and 97 are normally concentric, a slight sidewise motion or sliding of the inner apparatus carried by the base plate 303, with movement of the feet 39 in the slide cups 239, results in the brake surface 119 coming into contact momentarily with the brake band 316. As pointed out previously, during the extraction or centrifugal drying operation of the apparatus, the control shaft rotates at the speed of the tubular shaft 58, causing the container 23 to rotate about the axis of the shafts, 58 and 59 at the speed thereof, which may be of the order of 600 R. P. M. for example. If unbalance of the articles placed in the container 23 causes sidewise motion of the apparatus carried by the base plate 203, the momentary friction between the brake band 316 and the inner surface 119 of the brake drum 97 secured to the shaft 59 causes the shaft 59 to slow down thus reducing the speed of rotation of the container 23. Furthermore a temporary reduction in speed of rotation of the container 23 provides additional time for water to drain out while the rotation speed of the container is low enough to avoid objectionable vibration after sidewise motion caused by unbalance has diminished with reduced speed the brake surfaces no longer rub and the container resumes full speed. By this time sufficient water may have drained from the container 23 so that no undesirable unbalance will remain.

The vibration overcoming braking arrangement of Fig. 15 is simple and rugged in construction, durable, with no parts to require adjustment and no moving parts other than the brake drum 97 itself which is already in use in connection with the washer controlling brake band 98. Since there are no other moving parts, the operation is instantaneous upon a predetermined degree of vibration having taken place. The operation is also automatic in the sense that before the sidewise motion of the apparatus mounted upon the base plate 203 can increase to such value as to be objectionable on account of approaching the outer casing 301, contact is made between the inner brake surface 119 and the brake band 316. This contact slows up the action and allows time for some additional drainage of water to take place as already described.

It has already been pointed out that the imperceptible sidewise vibration or motion of the base 303 is provided for by freedom of motion of the feet 309 in the slide cups 239, and therefore such sidewise motion has no objectionable effects. It is only when the unbalance is so great as to cause such a great motion of the casing as to be in danger of moving the feet beyond the boundaries of the slide cups 239, or to bring the inner apparatus into contact with the outer casing 301 that there is any necessity for operation of the vibration-preventing braking mechanism including the brake surfaces 316 and 119.

Thus the same causes which might produce excessive movement of the feet 39 in the slide cups 239 or excessive movement of the tub with respect to the clearance space 306 within the casing 301 also bring about closing at some point of the clearance space 317 between the brake surface 119 and the brake band 316 so as to overcome the causes for sidewise motion.

It will be observed that in the arrangement of Fig. 15 the hydraulically stabilized foot 39' employing the hydraulic stabilizer 41 is one of the four feet mounted on the base plate 303 of the interior apparatus; and the outer casing is provided with manually adjustable feet 281.

However the invention is not limited thereto, and if desired the automatic foot adjustment may be provided on the outer casing 301 as illustrated in Fig. 16 for example. In that case there are three manually adjustable feet 283 and an automatically adjustable foot 318 controlled by the hydraulic stabilizer 41.

Fig. 16 represents a machine of the type shown in Fig. 15 with the apparatus mounted within an outer casing 301 but with the movable supports mounted relatively high with respect to the floor and bottom of the outer casing 301 so as to be relatively close to the center of gravity of the movable apparatus. In this case, the base 303 for the apparatus is mounted relatively high with various parts of the operating mechanism underslung instead of being mounted above the base 303 as in the arrangements of Figs. 1 and 15.

The motor 24 has an extended shaft 319 protruding downward through an opening 321 in the base plate 303. The base plate 303 is bolted directly to the pedestal 55 above the flange 56 thereof, and supporting feet 322 corresponding to the feet 39 in the apparatus of Figs. 1 and 15 are secured directly to the plate 303 positioned near the corners thereof. As will be explained more in detail hereinafter, one of the feet 322 is placed a slight distance from the corner of the plate 303.

A square bed frame composed of square steel tubing 323, for example, welded together is provided for supporting the lower edges of the cabinet or casing 301. The arrangement of the supporting frame work 323 is shown mechanically in Fig. 17 representing a view of the portion of the apparatus of Fig. 16 below the line 17-17. In this case the slide cups 239 are threaded into the top surfaces of the frame tubing 323. The sectional view of Fig. 16 is assumed to be a view of the section cut by a broken vertical plane 16-16 passing through the center vertical axis of the apparatus and through the axes of the supporting feet 283 and 318 of Fig. 16. The corner portions of the base plate 303 and of the frame work 323 have been assumed to be broken away. In order to provide space for the upwardly extending hydraulic stabilizer 41, one of the corners 324 of the base plate 303 has been cut out and the slide cup 239 and slideable foot 322 which would normally have been placed in that corner have been moved slightly along the edge as represented in Fig. 17.

The stationary brake drum for the vibration-preventing apparatus may be somewhat shorter than in the arrangement of Fig. 15 and accordingly a brake drum 325 is provided which is rigidly secured to the base frame work 323 of the outer casing 301 by means of a strap 326 riveted or bolted to the lower surfaces of the side strip 323, the ends of the supporting strap 326 being broken away for the sake of clarity in Fig. 16. The function and operation of the stationary brake band 316 and the inner braking surface 119 of the brake drum 97 are, however, the same as described in connection with Fig. 15.

The tub 30 is in this case supported upon the base plate 303 by means of suitable connections such as angle-plate brackets 327.

As illustrated in Figs. 15 and 16, means are provided for supporting the washing machine carriage with limited sidewise freedom of motion or freedom to sway. In the arrangement of Fig. 16 the base plate 303 of the carriage is swayingly supported at an elevated point with respect to the bottom of the outer casing 301 by means of feet 322, slideable in cups 239. My invention is not, however, limited to the specific arrangement illustrated for swayingly supporting the washing machine carriage, or providing sidewise freedom of motion. For example, as illustrated in Fig. 18, loose columns or pins may be provided for giving sidewise freedom of motion. Fig. 18 is a fragmentary view representing one corner of an apparatus such as that shown in Fig. 16. A pin 329 is provided in or near each corner of the casing in a position corresponding to the position of the slide cup 239 of Fig. 16. 75

In place of the slideable foot 322, indicated in Fig. 16 and Fig. 17, a button member 331 is provided, which is adapted to receive the upper end of the pin 329. A support in the form of a plate or disc 332 is arranged so that the lower end of the pin 329 may rest thereon. The pin 329 is free to pivot or swing in any direction around its contact with the button 331, and is, likewise free to pivot or swing in any direction around the point of contact with the plate 332. Thus the plate 303 is movable with respect to sidewise motion and substantially rigid with respect to up and down motion. For maintaining the contact of the upper end of the pin 329, at substantially a given point with respect to the plate 303, a socket 333 or the like is provided in the member 331. Similarly, a socket or other means may be provided for maintaining the lower end of the pin 329 at substantially a given point on the support 332.

Preferably, means are provided for resiliently retaining the pin 329 normally in a substantially vertical position. For example, a tube 334 may be mounted in an opening appropriately formed in the upper and lower plates of the base strip 333, and the disc 332 may form the lower end of the tube 334. Suitable resilient material such as soft vulcanized rubber, or air-filled cellular rubber of the type known as sponge rubber 335, may be provided for filling the space between the inner surface of the tube 334 and the pin 329.

While I have described a particular embodiment of my invention and certain apparatus for carrying out my method, it will be obvious to those skilled in the art that various modifications may be made without departing from the spirit of my invention, and I therefore desire to cover all such modifications as fall within the scope of my invention which is set forth in the appended claims.

35 What is claimed is:

1. In a washing machine, a rotatable driving member, a bearing carried by said member having a rotation axis inclined to the axis of rotation of said member, a container carried by said bearing for holding articles to be washed, means for rotating said member, a brake shaft engaging said container at its center so as to rotate therewith, said brake shaft having an axis of rotation concentric with the rotation axis of said member, centrifugal clutch fingers carried by said brake shaft and a clutch member carried by said driving member adapted to be engaged by said clutch fingers upon rotation of said shaft, so constructed and arranged that rotation of said driving member with the brake shaft released causes engagement of said clutch finger with said clutch and rotation of said shaft and said container at the speed of said driving member.

2. In a combined washer and extractor, a clothes container having a peripheral wall provided with liquid discharge passages, the container having a central re-entrant bottom portion, a tubular upright supporting shaft, a bearing mounted in the upper end of the supporting shaft with its axis disposed at a small fixed angle to the axis of the supporting shaft, a stub shaft mounted in the bearing and fixed to the container re-entrant portion, the arrangement being such that the axis of the stub shaft intersects the axis of the supporting shaft at the central zone of the container, and means for concurrently driving both said shafts.

3. In a combined washer and extractor, a clothes container having a peripheral wall provided with liquid discharge passages, the container having a central re-entrant bottom portion, a tubular upright supporting shaft, a bearing mounted in the upper end of the supporting shaft with its axis disposed at a small fixed angle to the axis of the supporting shaft, a stub shaft mounted in the bearing and fixed to the container re-entrant portion, the arrangement being such that the axis of the stub shaft intersects the axis of the supporting shaft at the central zone of the container, means for driving the tubular shaft relative to the stub shaft during washing to impart rapid "up

and down" movements to the container wall, and means for rotating the stub shaft and container at relatively high speed during extraction.

4. That method of washing and extracting in a symmetrical container which comprises moving the container about a point on the central axis thereof to cause all other points on said axis to move in a circular path with a predetermined angular velocity whereby the container is progressively tilted to effect washing and thereafter rotating said container about said axis with substantially the same angular velocity to effect extraction.

5. That method of washing and extracting in a substantially circular container which comprises progressively moving the container about a point on the central axis of the container so that all other points on said axis move in a circular path with a fixed angular velocity and at the same time restraining said container from rotation about said central axis and thereafter rotating said container about said axis at said same fixed angular velocity.

6. A laundry machine comprising a container having a circular bottom and side walls defining substantially a surface of revolution about an axis normal to the bottom of the container, the central portion of the bottom of said container being re-entrant to provide a hub for distributing the contents of the container and a drive housing, drive means rotating at a fixed predetermined angular velocity extending into said housing, means to connect said drive means to said container for concurrent rotation therewith and with the said axis of the container maintained at an angle to the axis of rotation of said drive means, a second means to connect said drive means to said container including a bearing with the axis thereof disposed angularly with respect to the axis of the drive means and intersecting said last named means within said housing whereby a point on the side wall of the container describes a closed curved path and moves around said path in a period of time corresponding to the time required for the same point to move about the said container axis when said container and drive means axes are connected for concurrent rotation.

7. That method of washing and extracting in a vertically disposed container having a substantially circular cross section throughout its height which comprises moving said container about a point on the central axis thereof above the bottom of the container and below the top thereof so that all other points on said axis move in a circular path with a predetermined angular velocity and at the same time restraining the container against rotation about said axis whereby the container is moved to cause a point on the side wall of the container above the horizontal plane through said first named point to travel about an elliptical path in one direction and a point on the wall of the container below said plane to follow an elliptical path in an opposite direction, to effect washing of the container contents and thereafter rotating said container about said axis with said same angular velocity to effect extraction.

8. A washing machine comprising an open top container having a substantially circular cross section throughout its height and a re-entrant bottom portion, a fixed supporting pedestal extending vertically to said re-entrant bottom portion, a pair of vertically extending concentric shafts mounted for rotation in said pedestal, means to rotate one of said concentric shafts and means within said re-entrant bottom portion connecting the container to said one shaft during said rotation, said last named means including a bearing with the axis thereof fixed at an angle with respect to said one shaft whereby the central axis of the container tilts about a point on the axis thereof within said re-entrant portion to effect washing of the container contents.

9. A washing machine comprising an open top container having a substantially circular cross section throughout its height and a re-entrant bottom portion, a fixed supporting pedestal extending vertically to said re-entrant

bottom portion, a pair of vertically extending concentric shafts mounted for rotation in said pedestal, means to rotate one of said concentric shafts and means within said re-entrant bottom portion connecting the container to said one shaft during said rotation, said last named means including a bearing with the axis thereof fixed at an angle with respect to said one shaft whereby the central axis of the container tilts about a point on the axis thereof within said re-entrant portion to effect washing of the container contents and means within said re-entrant portion connecting said one shaft to said other shaft for concurrent rotation to effect extraction.

10. In a washing machine, a rotatable driving member, a bearing carried by said member having a rotation axis inclined to the axis of rotation of said member, a container carried by said bearing for holding articles to be washed, means for rotating said member, a brake shaft operably connected to said container at its center so as to rotate therewith, said brake shaft having an axis of rotation concentric with the rotation axis of said member, brake means movable to one position to engage said brake shaft whereby relative rotation between said member and shaft effects washing action in said container and movable to another position to release said brake shaft and effect synchronous rotation of said two shafts.

11. In a washing and extracting machine, a vertically disposed rotatable driving member, a bearing secured to the upper end of said member having a rotation axis inclined to the axis of rotation of said member, a container carried by said bearing for holding articles to be washed, means for rotating said member and through said bearing rotating said container for extracting a brake shaft operably connected to said container at its center so as to rotate therewith, said brake shaft having an axis of rotation concentric with the rotation axis of said member, brake means operable to engage said brake shaft whereby relative rotation between said member and shaft effects a washing action.

12. In a washing machine, a rotatable driving member, a bearing secured to said member having a rotation axis inclined to the axis of rotation of said member, a clothes container having agitation means therein carried by said bearing, means for rotating said member and through said bearing rotating said container, a brake shaft secured to said agitation means so as to rotate therewith, said brake shaft having an axis of rotation concentric with the rotation axis of said member, brake means operatively engaging said shaft to restrain rotation thereof and effect a progressive tilting of said agitation means in response to the relative rotation between said brake shaft and said driving member.

13. In a combined washer and extractor, a clothes container having a peripheral wall provided with liquid discharge passages, the container having a central re-entrant bottom portion, a tubular upright supporting shaft, a bearing mounted in the upper end of the supporting shaft with its axis disposed at a small fixed angle to the axis of the supporting shaft, a stub shaft mounted in the bearing and fixed to the container re-entrant portion, the arrangement being such that the axis of the stub shaft intersects the axis of the supporting shaft at the central zone of the container, and brake means for holding one shaft during the rotation of the other.

14. In a combined washer and extractor, a clothes container having a peripheral wall provided with liquid discharge passages, the container having a central re-entrant bottom portion, a tubular upright supporting shaft, means to rotate said shaft, a bearing mounted in the upper end of the supporting shaft with its axis disposed at a small fixed angle to the axis of the supporting shaft, a stub shaft mounted in the bearing and fixed to the container re-entrant portion, means to rotate the stub shaft and container, the arrangement being such that the axis of the stub shaft intersects the axis of the supporting shaft at

the central zone of the container, and brake means for holding one shaft during the rotation of the other.

15. In a combined washer and extractor, a clothes container having a peripheral wall provided with liquid discharge passages, the container having a central re-entrant bottom portion, a tubular upright supporting shaft, a bearing mounted in the upper end of the supporting shaft with its axis disposed at a small fixed angle to the axis of the supporting shaft, a stub shaft mounted in the bearing and fixed to the container re-entrant portion, means for concurrently driving both of said shafts, and brake means for holding one of said shafts during the rotation of the other.

16. In a combined washer and extractor, a clothes container having a peripheral wall provided with liquid discharge passages, the container having a central re-entrant bottom portion, a tubular upright supporting shaft, a bearing mounted in the upper end of the supporting shaft with its axis disposed at a small fixed angle to the axis of the supporting shaft, a stub shaft mounted in the bearing and fixed to the container re-entrant portion, means for concurrently rotating both of said shafts at the same speed, and brake means for holding one of said shafts while the other is rotating at said speed.

17. In a combined washer and extractor, a clothes container having a peripheral wall provided with liquid discharge passages, the container having a central re-entrant bottom portion, ribs secured to said container having portions thereof terminating adjacent said central re-entrant portion and adapted to underlie clothes contained therein, a tubular upright supporting shaft, a bearing mounted in the upper end of the supporting shaft with its axis disposed at a small fixed angle to the axis of the supporting shaft, a stub shaft mounted in the bearing and fixed to the container re-entrant portion, the arrangement being such that the axis of the stub shaft intersects the axis of the supporting shaft at the central zone of the container, means for rotating said stub shaft and container for extraction, means to prevent rotation of said stub shaft and container and means to rotate said supporting shaft coincident with the non-rotation of said stub shaft to effect washing.

18. In a combined washer and extractor, a clothes container having a peripheral wall provided with liquid discharge passages, the container having a central re-entrant bottom portion, ribs secured to said container having portions thereof terminating adjacent said central re-entrant portion and adapted to underlie clothes contained therein, a tubular upright supporting shaft, a bearing mounted in the upper end of the supporting shaft with its axis disposed at a small fixed angle to the axis of the supporting shaft, a stub shaft mounted in the bearing and fixed to the container re-entrant portion, the arrangement being such that the axis of the stub shaft intersects the axis of the supporting shaft at the central zone of the container, means for rotating said stub shaft and container at a predetermined speed for extraction, means to prevent rotation of said stub shaft and container and means to rotate said supporting shaft at said same predetermined speed coincident with the non-rotation of said stub shaft to effect washing.

19. In a combined washer and extractor, a clothes container having a peripheral wall provided with liquid discharge passages and inclined washing ribs, a tubular upright supporting shaft for said container, a bearing fixed at the upper end of the supporting shaft with its axis disposed at a small fixed angle to the axis of the supporting shaft, a stub shaft rotatably mounted in the bearing and operatively connected to the container, means for driving the tubular shaft relative to the stub shaft to impart thereto circular motion with a predetermined angular velocity to reciprocate portions of the container vertically with accelerations exceeding the acceleration due to gravity to effect washing, and means to rotate said

stub shaft on its axis with the same angular velocity to effect extraction.

20. A laundry machine comprising a vertically disposed open top container having a circular bottom and side walls defining substantially a surface of revolution about the central axis of the container, vertically disposed drive shaft means rotating with a fixed angular velocity, means to connect said drive shaft means to said container for concurrent rotation whereby a point on the side wall of the container moves around the central axis thereof with said same fixed angular velocity to effect an extracting operation and a second means to connect said container to said drive shaft means with the said container axis intersecting the axis of the drive shaft means at an angle, said second means including a member restraining rotation of the container about said central axis whereby said point on the side wall thereof travels about an elliptical path with said same angular velocity to effect a washing operation.

21. A laundry machine comprising a container having agitating means therein, drive means including a vertical shaft rotating with a fixed angular velocity, means connecting said agitating means to said drive means including a bearing with the axis thereof angularly disposed with respect to the axis of the drive means and concentric with respect to the axis of the agitating means whereby a point on the agitating means moves about a closed curved path with the same angular velocity as said drive means and means connecting said container and drive means to rotate the container about an axis coincident with the axis of the drive means at said same angular velocity.

22. In a combined washer and extractor, a clothes container having a peripheral wall provided with liquid discharge passages, the container having a central re-entrant bottom portion, a tubular upright supporting shaft, a bearing mounted in the upper end of the tubular shaft at an angle to the axis of said tubular shaft, a stub shaft mounted in the bearing adapted to be moved in a fixed conical path during washing, the stub shaft axis intersecting the supporting shaft axis at the central zone of the basket, the stub shaft being fixed to the container re-entrant portion, means for rotating said bearing end thereby moving the stub shaft in said conical path during washing at a speed which will cause at least the peripheral zone of the container base to be reciprocated vertically at a rate exceeding the acceleration of gravity, and means to rotate the container at a speed to extract liquid from clothes disposed therein and to discharge liquid through said passages.

23. In a washing machine, a base, a casing supported by said base, vertically disposed pedestal projecting upwardly from said base within the casing, a pair of concentrically arranged rotatable drive shafts mounted in said pedestal, a clothes container on said pedestal within the upper portion of said casing, said container being circular in cross section throughout and having an open top to receive the clothes to be washed, said container having a bottom wall adapted to underlie the clothes and side walls sloping upwardly and outwardly from the bottom to provide a maximum diameter section intermediate the height of the container having apertures for the centrifugal extraction of liquid, means to connect one of said drive shafts to the bottom of said container centrally thereof for concurrent rotation of said drive shaft and container for centrifugal extraction and means to operatively connect the other of said drive shafts to the bottom of said container, said last-named means including a portion depending from the bottom of the container engaging a member carried by said other shaft to tilt the said axis of the container with respect to the axis of said other shaft and thus wobble the container in response to rotation of said other shaft, a power unit, means connecting said power unit to said other drive shaft for rotating the same at a rate effective to move

portions of said container bottom vertically with an acceleration exceeding the acceleration of the clothes above said portions due to gravity and means connecting said power until to said one drive shaft to rotate the container at a rate to effect centrifugal extraction.

24. In a washing machine, a base, a casing supported by said base, vertically disposed pedestal projecting upwardly from said base within the casing, a pair of concentrically arranged rotatable drive shafts mounted in said pedestal, a clothes container on said pedestal within the upper portion of said casing, said container being circular in cross section throughout and having an open top to receive the clothes to be washed, said container having a bottom wall provided with a re-entrant central portion, means to connect one of said drive shafts to the bottom of said container centrally thereof for concurrent rotation of said one drive shaft and container for centrifugal extraction, said other drive shaft having a bearing portion with its axis at an angle to the axis of said other drive shaft and means to operatively connect the said other drive shaft to the bottom of said container, said last-named means including a portion depending from the bottom of the container journaled in said bearing carried by said other shaft to tilt the said axis of the container with respect to the axis of said other shaft and thus wobble the container in response to rotation of said other shaft, a power unit, means connecting said power unit to said other drive shaft for rotating the same at a rate effective to move portions of said container bottom vertically with an acceleration exceeding the acceleration of the clothes above said portions due to gravity and means connecting said power unit to said one drive shaft to rotate the container at a rate to effect centrifugal extraction.

25. In a washing machine, a vertically disposed pedestal, a pair of concentrically arranged rotatable drive shafts mounted in said pedestal, a clothes container on said pedestal, said container being circular in cross section throughout and having an open top to receive the clothes to be washed, said container having a bottom wall adapted to underlie the clothes and side walls sloping upwardly and outwardly from the bottom to provide a maximum diameter section intermediate the height of the container having apertures for the centrifugal extraction of liquid, means to connect one of said drive shafts to the bottom of said container centrally thereof for concurrent rotation of said drive shaft and container for centrifugal extraction and means to operatively connect the other of said drive shafts to the bottom of said container, said last-named means including a portion depending from the bottom of the container journaled in a member carried by said other shaft to tilt the said axis of the container with respect to the axis of said other shaft and thus wobble the container in response to rotation of said other shaft, a power unit, means connecting said power unit to said other drive shaft for rotating the same at more than three hundred revolutions per minute to move portions of said container bottom vertically at a rate exceeding the rate the clothes above said portions may fall due to gravity and means connecting said power unit to said one drive shaft to rotate the container at more than three hundred revolutions per minute to effect centrifugal extraction.

26. In a washing machine, a base, a vertically disposed pedestal projecting upwardly from the base, a pair of concentric drive shafts rotatably mounted in the pedestal, a container for clothes mounted on said pedestal, said container being in the form of a surface of revolution and having a bottom and an open top, means to connect said container to one of said shafts for wobbling the container for washing comprising a member fixed to and depending from the said container bottom co-axially of the container axis, said member being engaged with said one drive shaft with the axis of said member intersecting the axis of said one drive shaft at a pre-

determined angle whereby said member is moved in a conical path in response to the rotation of said drive shaft and the container is wobbled about a point on the axis of the container, means to connect said other drive

5 shaft to the bottom of said container for concurrent rotation therewith, and means to rotate said one drive shaft at least three hundred revolutions per minute to move portions of the container vertically at a rate exceeding the rate at which the clothes above said portions may fall due to gravity.

27. In a washing machine, a base, a vertically disposed pedestal projecting upwardly from the base, a pair of concentric drive shafts rotatably mounted in the pedestal, a container for clothes mounted on said pedestal, said container being in the form of a surface of revolution having a diameter of substantially 22 inches and having a bottom and an open top, means to connect said container to one of said shafts for wobbling the container for washing comprising a member fixed to and depending from the said container bottom co-axially of the container axis, said member being engaged with said one drive shaft with the axis of said member intersecting the axis of said one drive shaft at a predetermined angle whereby said member is moved in a conical path in response to the rotation of said drive shaft and the container is wobbled about a point on the axis of the container in the central zone thereof, means to connect said other drive shaft to the bottom of said container for concurrent rotation therewith, and means to rotate said one drive shaft to move portions of the container vertically a distance more than twice the distance the clothes above said portions may fall due to gravity during the same era of time.

28. In a combined washer and extractor, a clothes container having an open top to receive the clothes to be washed, a re-entrant bottom portion and a peripheral wall provided with liquid discharge passages, a base, a vertical pedestal fixed to the base and extending upwardly therefrom into the re-entrant bottom portion of said container, a vertical tube rotatably mounted within said pedestal and a vertical shaft mounted within said tube, a motor carried by the base and operatively connected at the bottom of said pedestal to said tube and shaft, a bearing mounted at the upper end of said tube at an angle to the vertical axis thereof, a stub shaft fixed to said container in said re-entrant bottom portion and having the lower end thereof mounted in said inclined bearing; said tube being rotated by said motor during washing to successively raise and lower portions of the container remote from its central axis at a rate which exceeds the acceleration due to gravity that may be imparted to clothes and water in the container, said container being rotated by the motor during extraction to centrifugally discharge liquid through said passages.

29. In a combined washer and extractor, a clothes container having an open top to receive clothes and water, said container being in the form of a surface of revolution and having a re-entrant bottom portion at the center of the container, said container having liquid discharge openings in the peripheral wall thereof, a base, a vertical pedestal carried by the base and projecting upwardly therefrom into the re-entrant container portion, a vertical drive tube rotatable in the pedestal and a vertical shaft within said tube, a bearing mounted on said tube at the upper end thereof at an angle to the vertical axis of the tube, a stub shaft depending from the bottom of the container at said central re-entrant portion rotatably mounted in said inclined bearing, universal joint means to couple the lower end of said stub shaft to said vertical shaft within the tube, motor means to rotate the tube to successively tilt the container and thereby raise and lower portions of the container at a rate exceeding the rate the clothes and water therein may be accelerated due to gravity and means to rotate the container to centrifugally

discharge liquid through said openings in the wall of the container.
